GAS WASHER

Orrin E. Fenn, Detroit, Mich., assignor to Peters-Dalton Inc., Detroit, Mich., a corporation of Michigan

Application August 30, 1945, Serial No. 613,559

9 Claims. (Cl. 261—119)

1

This invention relates to improvements in liquid contact gas washers.

An object is to provide a liquid contact gas washer of the horizontal type and which may be disposed beneath the floor or suspended from the ceiling of a building whereby space may be economized and a more convenient hookup obtained with air ducts leading from different machines and from manufacturing operations in industrial plants. Obviously the washer may be supported upon the floor in the usual manner if such is desired.

Another object is to provide an air or gas washer of the character described which is of simple construction and employs a minimum amount of apparatus to accomplish a satisfactory washing of the air. More particularly an object is to provide a washer of the character set forth wherein the air to be washed is caused to travel generally in a horizontal direction over a layer of liquid, such as water, which liquid covers the bottom of the passageway, and the air as it pursues its horizontal path of travel is successively directed downwardly toward such layer of liquid and the wetted foreign particles in the air stream are thrown out of the air stream into such liquid mass.

A further object is to provide a gas washer of the character described wherein the air is first directed downwardly toward the layer of water which covers the bottom wall of the passageway to throw the heavy foreign particles from the air stream into the liquid and the air is then directed upwardly to create a swirling mass of liquid and air rotating about a horizontal axis which extends transversely of and above the liquid mass and wherein the finer particles of foreign material are wetted and such wetted foreign particles are thereafter thrown into the liquid mass as the air stream is directed downwardly.

The swirl of liquid and air wherein the particles of foreign material carried by the air are wetted may be creased by the air stream picking up liquid from a selected portion of the liquid mass as the air travels thereover at a relatively high velocity or the air may pick up liquid from a liquid curtain through which the air is passed or liquid may be sprayed into the air stream.

A meritorious feature resides in the provision of a casing having an air inlet at one end and an air outlet at the opposite end and defining a generally horizontal air passageway which casing is provided interiorly with a plurality of transversely disposed baffles spaced apart lengthwise

of the casing. These baffles are staggered so that the air stream in passing through the casing is deflected to pursue a sinuous generally horizontal path. In other words the air stream is successively directed upwardly and then downwardly as it flows horizontally through the casing. These baffles further serve as moisture eliminators to remove entrained moisture from the air stream.

Preferably certain of the baffles depend from the ceiling of the passageway and terminate at the bottom spaced above the level of the liquid and alternate baffles extend upwardly from below the liquid level to a point thereabove and overlap the downwardly extending baffles. The baffles which extend upwardly from below the liquid level preferably also define openings below the liquid level which openings permit the flow of liquid over the floor of the passageway underneath the baffles so that the liquid collected foreign particles may be carried to one end of the liquid sump in the bottom of the casing.

In one preferred embodiment the top wall of the casing slopes at a gradual incline downwardly toward the air inlet end of the casing and there is an inlet baffle which extends downwardly from this top wall toward the liquid level and which baffle is bent inwardly along its lower margin toward the air outlet end of the casing. Means is provided for delivering water onto the top wall of the casing to flow thereover and also over the outer face of the inlet baffle to drop therefrom across the air inlet into the casing and into the liquid sump. A floor grill extends over the top wall of the casing above the sheet of liquid flowing thereover and air enters through this grill to flow downwardly toward the liquid sump to enter through the inlet into the casing. Means is provided to maintain a determined level of liquid upon the floor of the casing.

Preferably the construction is such that liquid is carried through the air inlet into that portion of the casing adjacent thereto which constitutes a washing chamber and in one construction there is provided a flow plate which extends from a submerged position below the liquid level and adjacent to the air inlet into the casing upwardly and rearwardly at a slight incline and the liquid level is so maintained that a relatively thin sheet of liquid is established over a portion of this inclined flow plate. As the air enters at a high velocity through the inlet and flows over the thin water sheet upon the flow plate it picks up the water therefrom and carries it into the washing space within the casing.

Other objects, advantages and meritorious fea-

tures of this invention will more fully appear from the following description, appended claims and accompanying drawings, wherein:

Figure 1 is a vertical sectional view through a washer embodying my invention.

Figure 2 is a vertical sectional view through washer of the same general character as is illustrated in Figure 1 but showing a sludge conveyor combined therewith to withdraw foreign material collected in the liquid sump.

Figure 3 is a vertical sectional view through a modified form of washer embodying the invention and particularly adapted for use in conjunction with a paint spray booth.

Figure 4 is a vertical sectional view through a second modified form of the washer.

Liquid contact gas washers of the general character to which this invention relates are commonly termed air washers. They are used in industry to remove dust particles which arise as a result of grinding or other dust producing operations and to remove paint particles which arise as a result of paint spraying operations. The air that is fouled by the dust, paint or other foreign particles is collected and caused to pass through the liquid contact washer. The object is to wet the foreign particles carried by the air stream so as to cause them to leave the air stream and to settle in a liquid sump wherein they may be collected and from which they may be removed. The washer is so constructed that entrained moisture is removed from the air stream so that the cleaned air will not be unduly heavy with moisture. The cleaned air may be discharged into the building from which it is taken or it may be discharged exteriorly thereof depending upon the demands.

A common type of construction heretofore in use has been an upright casing having an air inlet at the bottom and an air outlet at the top. By one means or another a liquid spray or shower was created within a portion of the casing and the air was passed upwardly therethrough for washing and thereafter was passed over moisture eliminators for removal of moisture and the discharge of clean air from the outlet of the casing. Washers of this type consumed considerable floor space. A feature of the instant invention is to provide an air washer wherein the air flows in a generally horizontal direction therethrough and the casing may be suspended from the ceiling or below the floor of a building. Such a construction is economical of floor space and is adaptable for convenient association with various dust producing devices.

The casing of the instant air washer may be of a generally rectangular shape in transverse cross sectional vertical area. In Figure 1 a casing is shown as having a floor 10. This floor slopes downwardly toward an end portion 12 of the casing wherein foul material which falls into the liquid which covers the floor of the casing may be collected. The liquid level is indicated as 14. The ceiling of the casing is indicated as 16 and the casing is provided with suitable sides and end walls. An air downdraft conduit 18 leads into one end of the casing and an air outlet 20 leads away from the opposite end of the casing.

A liquid makeup conduit 22 is provided to deliver liquid into the liquid sump portion of the casing. An overflow conduit 24 is provided to maintain a determined liquid level within the casing. A drain conduit 26 is provided whereby the liquid sump may be drained. In the construction shown in Figure 1 the collector basin

portion 12 at one end of the casing is separated from the main portion thereof by an intermediate wall 27. This wall 27 extends below the water level and the makeup conduit 22 delivers fresh water into the main portion of the casing. This intermediate baffle wall 27 serves to assist in maintaining the foul particles within the end portion 12 of the sump once they are collected therein and in preventing their recirculation back into the main portion of the sump of the casing.

A plurality of baffles are arranged within the interior of the casing. These baffles extend transversely across the casing and are spaced apart lengthwise thereof. The baffles are staggered and as here shown alternate baffles extend downwardly from the ceiling toward the liquid level and upwardly from below the liquid level toward the ceiling. The upwardly extending baffles terminate spaced above the liquid level and spaced below the ceiling. The downwardly extending baffles terminate spaced above the liquid level. The plurality of baffles define an air passageway which is of a generally horizontal character but wherein the air is first directed upward and then downwardly or along a sinuous generally horizontal path.

In the construction shown there is a wall portion 28 which may be termed the inlet baffle which extends downwardly from adjacent to the air inlet toward the liquid level and is then curved inwardly above the liquid level toward the outlet end of the casing. The curved lower portion of this baffle is spaced a relatively small distance above the liquid level defining the minimum transverse cross sectional area of the air passageway through the casing. An intermediate baffle 30 also extends transversely across the casing between the two side walls, as does the baffle 28. This baffle 30 extends upwardly as shown from below the liquid level but from a point spaced above the floor 10 of the casing. The upper margin of this baffle is curved toward the baffle 28 as shown.

Between these two baffles 28 and 30 there is formed what may be termed a washing chamber. A plate 32 slopes from the upright portion of the baffle 28 to the inner margin of its curved lower portion bridging the concavity so that water will not collect therein. One or more moisture eliminator baffles may be provided and in Figure 1 such a baffle 34 is shown as depending from the ceiling overlapping the baffle 30 and terminating spaced above the liquid level. As the air enters the casing it is first directed downwardly through the downdraft 18 toward the liquid in the sump. From there it passes through the inlet into the casing and turns upwardly through the washing space between the baffles 28 and 30 and over the top of baffle 30 and is then directed downwardly by baffle 34 before it enters the outlet 20 upon which a suction may be imposed.

In this construction of Figure 1 there is provided a flow plate 36 which extends from an upright portion 38 submerged below the air inlet 18 at a slight inclination upwardly and rearwardly to a point intermediate the baffles 28 and 30 where it terminates in a downwardly projecting portion 40. Due to the slight inclination of this plate liquid stands on top of the plate at a relatively shallow depth. The liquid level upon the plate together with the curved portion of baffle 28 defines a restriction through which the air flows at relatively high velocity as for example 4000 feet a minute. The air flowing through this restricted inlet picks up water from the flow plate

36 and carries it into the washing space between the baffles 28 and 30 where it is swirled about. The major portion of the water flows downwardly into the sump carrying with it the wetted foreign particles washed from the air. The water which strikes the wall or baffle 30 flows down such baffle and through the space between the baffle 30 and the upright wall 40 and into the sump without depositing the foul material picked up thereby upon the flow plate 36 from which water is picked up by the air stream to maintain the liquid swirl.

A portion of the water is carried over the top of baffle 30 and thrown against the baffle 34 from which it is knocked down into the liquid sump therebelow. This water and the particles of foreign material wetted thereby can flow underneath the baffle 30 and the walls 40, 38 and 27 into the end portion 12 of the casing.

Figure 2 illustrates the same general type of washer shown in Figure 1 and hereinabove described. The floor 10 of the casing shown in Figure 2 is of a hopper like construction. A fan 42 driven by an electric motor 44 is illustrated to draw air through the casing. The overflow 24 which maintains the water level is illustrated as differently positioned from what it is in Figure 1 but the result is the same. An endless sludge conveyor 46 is also illustrated. This leads from a collector basin 48 which collector basin is disposed at the low point of the hopper. This sludge conveyor and hopper structure are conventional. In this construction of Figure 2 the water level together with the curved lower portion of the baffle 28 defines the restricted air intake into the casing. Through it the air travels at a velocity to pick up liquid which stands on top of the flow sheet 36. The operation of the structure of Figure 2 is of the same character as has been described in connection with the construction of Figure 1 except for the addition of the sludge conveyor.

Figure 3 illustrates a modified form of construction wherein the tank floor 10 slopes downwardly toward one end at which there is a drain outlet 26 as has been described above. The overflow is indicated as 24 and maintains the water level 14. The air outlet 20 is at one end and the air inlet into the washing chamber portion of the casing is at the opposite end as illustrated. The ceiling 16 of the casing slopes downwardly from adjacent to the air outlet end toward the air inlet end. The inlet baffle 28 extends downwardly toward the water level and is bent along its lower margin inwardly toward the outlet end portion and there is a plate 32 which bridges across the concavity formed by the curved portion of this baffle as has been hereinabove described.

There is an intermediate upwardly extending baffle 30 which curves along its upper margin toward the baffle 28 to define between these two baffles a washing space within which a liquid swirl is created. There are then two other baffles, namely a downwardly projecting baffle 34 and an upwardly projecting baffle 35 which baffles act not only as water eliminators but also act to direct the flow of air so as to assist in removal of foreign wetted particles. There is a flow plate 36 having a depending upright portion 40 of the character hereinabove described.

This particular apparatus is especially suitable for use in conjunction with a paint spray booth and the makeup water is delivered through a conduit 22 into a collector trough 46 from which it

overflows to flow as a sheet over the upper surface of the top wall of the casing and down over the front surface of the front face of the baffle 28 to fall therefrom as a vertical curtain of water across the air inlet into the liquid sump. A floor grill 50 superimposes in spaced relationship the ceiling 16 of the casing permitting the water to flow thereunder. The air enters through this floor grill and particularly through a portion 52 thereof to pass downwardly into the casing toward the liquid in the sump. As the air is drawn into the inlet between the flow plate 36 and the curved lower portion of the baffle 28 it picks up water from the water curtain falling across the inlet and carries it into the washing space between the baffle 28 and the baffle 30.

In this construction the inlet is not so restricted in cross sectional area as are the inlets in the construction of Figures 1 and 2 due to the fact that in this construction the air travels through a vertical water curtain from which it can pick up water while in the construction of Figures 1 and 2 it must pick up the water from the surface of the sheet extending over the flow plate. Also in this construction a considerable quantity of the paint particles are deposited directly upon the sheet of water flowing over the upper surface of the top wall of the casing and over the front face of the baffle 28. Furthermore this upper surface of the top wall and the front face of the baffle 28 are kept clean by the water flowing thereover. Otherwise this construction is similar to those which have heretofore been described. The top wall of the casing may be provided with removable panels such as the one shown at 51 which may be withdrawn for cleaning the baffles. The baffles themselves may be removable for cleaning in this as well as in the other structures described.

In Figures 4 the construction resembles that of Figure 3 in that the casing is of a generally similar character provided with similarly identified constructional features except that the floor grill is of limited size and the water is not flowed over the top wall of the casing but merely over the front face of the baffle 28 being delivered to flow thereover from a flow pipe 54 which extends lengthwise along the top margin of the baffle 28 and showers water thereupon as shown. This flow pipe is covered by an enclosure 56 which enclosure defines an outlet through which the water flows down over the front face of the baffle and falls as a vertical curtain therefrom into the liquid sump. The operation of this construction of Figure 4 is the same as has been above described except that in addition to the water supplied to the front face of the baffle 28 there is provided a shower pipe 58 which is adapted to direct a spray of water upwardly against the baffle 30 and into the space between such baffle and the baffle 28. There is an adjustable plate 60 which may be slidably adjusted over the plate 32 to vary the extent of the air inlet between such plate 60 and the baffle 30.

What I claim is:

1. A gas washer comprising a casing defining a generally horizontally extending air passageway having an air inlet at one end and an air outlet at the opposite end, the lower portion of the casing constituting a liquid containing sump, a baffle extending downwardly from the top wall of the casing adjacent to the inlet and terminating at the bottom spaced above the liquid level in the sump, said top wall of the casing sloping downwardly toward the air inlet into the casing, means

for delivering liquid to flow downwardly over the top wall of the casing and over the front face of said inlet baffle to fall as a curtain across the air inlet into the casing, a floor grill extending spaced above the top wall of the casing permitting the flow of liquid over said top wall below said grill, means for causing air to enter the casing and flow therethrough and air flow deflecting baffles disposed transversely within the casing above the liquid level therein, said inlet baffle being bent along its lower margin toward the casing outlet, a baffle extending upwardly from below the liquid level and spaced above the floor of the casing and spaced rearwardly of said inlet baffle to a height above the lower margin of the inlet baffle and curved forwardly along its top margin toward said inlet baffle forming a washing chamber between said baffles, and means for maintaining a liquid level within said casing above the lower margin of said upwardly extending baffle and below the lower margin of said inlet baffle.

2. A gas washer comprising a casing defining a generally horizontally extending air passageway having an air inlet at one end and an air outlet at the opposite end, the lower portion of the casing constituting a liquid containing sump, a baffle extending downwardly from the top wall of the casing adjacent to the inlet and terminating at the bottom spaced above the liquid level in the sump, said top wall of the casing sloping downwardly toward the air inlet into the casing, means for delivering liquid to flow downwardly over the top wall of the casing and over the front face of said inlet baffle to fall as a curtain across the air inlet into the casing, a floor grill extending spaced above the top wall of the casing permitting the flow of liquid over said top wall below said grill, means for causing air to enter the casing and flow therethrough and air flow deflecting baffles disposed transversely within the casing above the liquid level therein, said inlet baffle being bent along its lower margin toward the casing outlet, a baffle extending upwardly from below the liquid level and spaced above the floor of the casing and spaced rearwardly of said inlet baffle to a height above the lower margin of the inlet baffle and curved forwardly along its top margin toward said inlet baffle forming a washing chamber between said baffles, and means for maintaining a liquid level within said casing above the lower margin of said upwardly extending baffle and below the lower margin of said inlet baffle, and a flow plate extending from below the liquid level in the sump and below the inlet baffle upwardly and rearwardly at a slight incline toward said upwardly extending baffle and terminating spaced between said baffles above the liquid level in the sump.

3. A gas washer apparatus comprising, in combination, a casing defining a generally horizontally extending air passageway having an air inlet into one end thereof and an air outlet at the other end thereof and provided with an inclined ceiling sloping downwardly toward the air inlet end thereof and an inclined bottom, a horizontal floor grill extending over said inclined ceiling, means for maintaining a liquid sump over the inclined bottom of the casing at a predetermined liquid level in the casing, means providing a liquid drain outlet in the lowermost part of said bottom for removing the sump liquid from the casing, two sets of baffles extending transversely across the casing and being spaced apart lengthwise thereof, one set of baffles extending downwardly from the ceiling of the casing and terminating spaced above said liquid level, the other set of

baffles alternating with the baffles of said first set and extending upwardly from below said liquid level and having the upper and lower edges thereof terminating in spaced relation to the ceiling and bottom of the casing respectively, said sets of baffles forming a generally horizontal sinuous air passageway above said liquid passageway and a liquid passageway over the inclined bottom of the casing under the second set of baffles, the first baffle of said sets of baffles extending downwardly from lower edge of the inclined ceiling and having the lower margin thereof curved inwardly toward the next succeeding baffle and in spaced relation to said liquid level to define the minimum cross sectional opening in said sinuous air passageway, said next succeeding baffle having its top margin curved toward said first baffle at a height spaced above the lower curved margin thereof and forming in combination therewith a washing chamber there-between, a liquid flow plate under the lower curved margin of said first baffle extending upwardly and inwardly at a slight incline from below said liquid level and terminating above said liquid level spaced from said first and said next succeeding baffles, means for delivering liquid to the upper end of said ceiling to flow down the upper surface thereof under said floor grill and over the front face of said first baffle to fall as a curtain across said minimum opening of the air passageway, and means for causing air to flow downwardly through said floor grill and to enter said air inlet of the casing and flow through said sinuous air passageway and out of said air outlet at such a speed that it picks up particles of said liquid curtain at said minimum opening and carries the same therewith into said washing chamber where it is swirled about before separation from the air.

4. In a gas washer, a horizontal casing having a gas inlet at one end and a gas outlet at the opposite end and provided with a top wall sloping toward the inlet, means for maintaining a determined liquid level within the casing, a floor grill extending over and spaced above the top wall, an inlet baffle projecting downwardly from the top wall and terminating spaced above the liquid level within the casing, means for causing the liquid to flow over the top wall and over said inlet baffle and to fall as a curtain across the gas passageway between said baffle and the liquid level in the casing, means for causing air to pass through the grill and through the inlet and over the inlet baffle into the casing and to pass underneath the inlet baffle through the water curtain falling thereacross and to travel through the casing.

5. In an air washer, a floor grill, a horizontal casing disposed underneath the grill having an air inlet at one end and an air outlet at the opposite end and provided with a top wall sloping toward the inlet, means for maintaining a determined liquid level within the casing, a baffle extending transversely across the casing and depending from the top wall at the inlet and having its bottom margin curved toward the outlet above the liquid level in the casing, means for causing liquid to flow over the top wall toward the inlet and down over the inlet baffle into the casing, means for causing air to pass through the grill and through the inlet and over the inlet baffle and to travel thereunder and through the casing, and a baffle extending transversely across the casing and projecting upwardly from below the water level and having its top margin curved toward

the inlet baffle spaced above the bottom margin thereof.

6. In an air washer, a casing having an air inlet and an air outlet and defining a horizontally extending air passageway therethrough between the inlet and the outlet, means for maintaining a determined water level within the casing, a substantially vertical inlet baffle depending from the top wall of the casing at the inlet and extending transversely across the casing, said baffle having its bottom margin curved spaced above the water level toward the air outlet, a substantially vertical water deflecting baffle extending transversely across the casing and projecting upwardly from below the water level, said baffle having its top margin curved toward the inlet baffle spaced above the curved bottom margin thereof forming a washing zone between the curved margins of the two baffles, means for causing air to flow through the casing entering at the inlet and passing underneath the inlet baffle and carrying water upwardly over the water deflecting baffle to be directed thereby toward the inlet baffle setting up a water swirl between the curved margins of said baffles.

7. In an air washer, a casing having an air inlet and an air outlet and defining a horizontally extending air passageway therethrough between the inlet and the outlet, means for maintaining a determined water level within the casing, a substantially vertical inlet baffle depending from the top wall of the casing at the inlet and extending transversely across the casing, said baffle having its bottom margin curved spaced above the water level toward the air outlet, a substantially vertical water deflecting baffle extending transversely across the casing and projecting upwardly from below the water level, said baffle having its top margin curved toward the inlet baffle spaced above the curved bottom margin thereof forming a washing zone between the curved margins of the two baffles, a flow plate extending transversely across the casing spaced below the curved margin of the inlet baffle and having a rear margin positioned between the edge of the curved bottom margin of the inlet baffle and the upwardly projecting water deflecting baffle above the water level, said flow plate sloping from said rear mar-

gin downwardly toward the inlet to a front margin spaced below the water level and disposed substantially in line with the vertical portion of the inlet baffle, said two margins of the flow plate having vertical portions depending below the water level, and means for causing air to flow through the casing entering at the inlet and passing underneath the inlet baffle and carrying water upwardly over the water deflecting baffle to be directed thereby toward the inlet baffle setting up a water swirl between the curved portions of said baffles.

8. The invention as defined in claim numbered 6 characterized in that a flow plate is provided which extends transversely across the casing spaced below the curved bottom margin of the inlet baffle and projecting upwardly from its front margin disposed below the water level toward the outlet end of the casing and to a rear margin spaced above the water level and spaced forwardly of said water deflecting baffle.

9. The invention as defined in claim numbered 6 characterized in that means is provided for delivering water into the space between the inlet baffle and said upwardly projecting baffle to be picked up by the air stream flowing through the casing.
